UNITED STATES PATENT OFFICE

2,146,291

CARD PERFORATOR WITH SPOT DETECTOR

Clement Ehret, White Plains, N. Y., assignor to
International Business Machines Corporation,
New York, N. Y., a corporation of New York

Application September 17, 1936, Serial No. 101,255

22 Claims. (Cl. 164—113)

This case relates to automatic accounting systems involving perforated records punched to represent information and which control tabulating, sorting, and other accounting machines in accordance with the punched holes in the records.

In order to accurately control the accounting machines, the cards must be free of any defects or flaws which might interfere with proper operation of the controlled machines. Particularly is this true where the control of the machines is effected electrically through electrical analyzing means which analyze or search the records for holes and in accordance with the analysis cause selective operation of the accounting machines. A record sheet or card for the electrically controlled machines must be free of conductive spots or any holes no matter how small through which a false analysis may be made by the card searching elements.

In order to prevent record cards defective by reason of conductive spots or other flaws to enter into the accounting system, it is desirable to eliminate the defective cards in the first stage of their preparation as control media. This first stage of preparation is to punch holes in the cards according to a selected code to represent desired data. The punching of holes in the cards is done by a perforating machine which has a keyboard for controlling it and usually an additional pattern card section for selecting the holes to be punched according to a prepared pattern punched in a master or pattern card.

The object of the invention may be stated as the elimination of defective cards during the punching operation or during their passage through the punching machine.

Further, the object is to detect flaws in the blank record card as it is fed to the punching station proper and in case of a defect being detected to withhold the punching of the card and to immediately pass the card through and past the punching station without accompanying operation of the punching means.

It is a further object to so treat the defective cards as to mark their defectiveness.

The latter object, more specifically, is to sever the defective cards lengthwise as they are fed out of the punching station to obviate any possibility of their being run through the punching machine again.

The above objects are accomplished by combining with the punching machine a device for detecting and destroying defective cards as they are run through the punching machine.

Other objects will be apparent from the further

parts of the specification and from the drawings, in which,

Fig. 1 is a side view of the machine.

Fig. 2 is a detail section taken through the spot detecting brushes.

Fig. 3 is a detail of the escapement feed release mechanism.

Fig. 4 is a plan view of the machine.

Fig. 5 is a detail central section through a portion of the machine.

Fig. 6 is a detail plan view of the rear part of the machine with a surface part broken away to show the interior, and

Fig. 7 is a circuit diagram.

The punching machine is of the type shown in Patent No. 1,772,186. Only such details of the punching machine will be described herein as are required for an understanding of the present invention. New parts may be referred to as special.

The machine has keys 10 depressible to select the punches for operation. Upon depression of a key 10, it acts through a connecting lever 11 to advance an interposer 12. The advance of the interposer brings the upper edge beneath a hammer tip 13 carried by a pressure plate 14. Before its advance, the interposer has a notched forward end below the hammer tip. Thus, upon depression of the hammer tip, it will not strike the interposers left in initial position but will strike the upper edge of the advanced interposer and force the latter downwardly to depress the punch 15 on which the interposer rests. The depressed punch 15 coacts with a die hole in die plate 16 to punch a hole in the work card T. The card has parallel columns of perforation-receiving positions (see Fig. 4) and the punches are arranged in a single line to selectively punch one card column at a time.

Keys 10 may be manually or automatically depressed to select the punches for operation. For automatic operation, they are connected to armature levers 17, the armature plates 18 of which are in cooperation with selecting magnets 20. The magnets are selectively energized under control of a pattern card P (see Fig. 4) the perforations of which are sensed by an analyzer comprising a set of ball contacts 21 (see Fig. 7) and a cooperating contact roller 22.

When a hole in a column of the pattern card comes beneath a ball 21, the latter protrudes through the hole into engagement with the contact roll and closes a duplicating circuit through a magnet 20 which operates the proper key for selecting the punch to duplicate the sensed pattern card hole in the work card T.

A typical duplicating circuit may be traced as follows (see Fig. 7):

Duplicating circuit.—From supply line 24, through normally closed contacts 25, 26, and 27, contact roll 22, the ball 21 engaged therewith through a perforation in the pattern card, the magnet 20 connected to this ball, common line 28, normally closed contact 29, special, normally closed relay contacts 30a of a special relay 30 and to the opposite supply line 32.

Energization of the magnet 20 acts through elements 18 and 17 to depress the associated key 10 for selecting the punch for operation. As explained before, the selection is effected by advancing an interposer to effective position below hammer tip 13 of pressure plate 14. The advance of any of the punch interposers causes contacts 33 (see Fig. 7) to close. The mechanical means for closing these contacts are not illustrated here, as these means are fully disclosed in the aforementioned Patent No. 1,772,186.

Upon closure of contacts 33, a punch operating circuit is closed as follows (see Fig. 7):

Punch operating circuit.—From line 32, through contacts 33, punch operating magnet 34, and to line 24.

Punch operating magnet 34, when energized, operates linkage 35 (see Fig. 5) to depress plate 14 causing hammer tip 13 to depress the advanced interposer 12 and the punch 15 underlying it, thus effecting punching of a hole in the card T.

Upon depression of the advanced interposer, the latter also rocks a bail 36 (Fig. 5) to rock a member 37 (Fig. 3) counterclockwise, thereby raising escapement pawl 38 from escapement rack 39 and lowering escapement dog 40 into engagement with the rack. The escapement rack is thereby held against advance. After the punching operation, upon return upwardly of the depressed interposer, bail 36 and member 37 return clockwise, causing dog 40 to release rack 39 and pawl 38 to again engage the rack. In the interim between release of the rack by pawl 38 and the return to engagement with the rack of the pawl, the rack is advanced one tooth distance equivalent to a column advance of the card.

For full details of the escapement mechanism, recourse may be had to Patent No. 1,426,223 or Patent No. 1,772,186 (Fig. 17).

Referring to Fig. 4, the escapement rack carries oppositely and laterally extending parts 42 and 43 respectively in rear of the pattern card P and work card T and also carries oppositely extending parts 44 and 45 respectively engaging the forward edges of the pattern and work cards. As may be seen from Fig. 5, part 43 pivotally carries a pusher element 46 for engaging the rear edge of the work card. Thus, upon advance of escapement rack 39, the pattern and work cards are constrained to move with the rack and to the same extent. Parts 42, 43, 44, 45, and 46 may be referred to as the card carriage.

The blank cards T to be punched are stacked in a supply magazine 48 at the rear of the machine. The bottom card of the stack is fed to the card carriage by a picker 50 (see Figs. 2, 4, and 6). Picker 50 is mounted on a bracket 51 which carries a finger handle 52. Bracket 51 is also rigidly connected to a slideable rod 53. To feed a card from magazine 48 to the card carriage, the operator grasps handle 52 and moves the parts connected thereto to the left (Fig. 1), through their forward stroke. Picker 50 which is engaged with the rear edge of the bottom card T thereupon advances the bottom card until the

rear edge of the card is in front of pusher 46 of the card carriage. The card is thus delivered to the card carriage.

During the forward stroke of the picker mechanism, the escapement mechanism and connected card carriage are returned to the right by connections to rod 53. The picker mechanism at the end of its forward stroke is automatically returned to its initial position while the card carriage remains in the rear position, in which the card delivered thereto has its first column in punching position. Column by column advance of the card is then effected incidentally to successive punching operations while the picker mechanism remains in rear position.

The picker mechanism and the return operation under its control of the escapement and carriage are fully disclosed in Patent No. 1,772,186 and need not be further explained herein.

When the picker mechanism is in rear position, the rear horizontal edge of bracket 51 is abutting a lug 55 formed on a horizontally rockable lever 56 (see Fig. 6) and is holding the lever to the right. In this position of the lever, its insulating piece 57 is forcing a spring blade 58 towards a spring blade 59. Blades 58 and 59 carry contacts 25 previously referred to in tracing the duplicating circuit. When blade 58 is forced towards blade 59 by piece 57, contacts 25 are closed. At the same time, a special insulating rod 61 secured to blade 59 is engaging a special spring blade 62 and holding its contact point 63 away from the companion point 63 on a special blade 64. Thus, initially, special contacts 63 are open and contacts 25 closed. At the beginning of the forward stroke of the picker mechanism, bracket 51 releases lug 55 of lever 56 and spring blade 58 moves away from blade 59, permitting contacts 25 to open and special contacts 63 to close. The purpose of contacts 63 will be brought out later.

In addition to the character keys 10 of the keyboard, the latter is provided with the usual release key R (see Fig. 4). Referring to Fig. 3, depression of release key R acts through a bell crank 66 to move a bar 67 to the right, causing the bar to ride up on its support 68. Bar 67 underlies a skip lifter 69 so that rise of bar 67 elevates the skip lifter. The latter, in turn, raises escapement pawl 38, thereby freeing escapement rack 39 for uninterrupted continuous advance to the end of its forward stroke. As rack 39 moves to the end of its forward stroke, the card carriage moves the work card T and pattern card P to the positions shown in Fig. 4. The work card T may then be removed by the operator. At the end of the forward stroke of the escapement rack, a member 69 carried thereby strikes the forward, downwardly bent end of release bar 67 and returns it to initial position.

Departing from previous construction, release key R is connected to a special armature lever 70 provided with an armature 30' (see Fig. 5) for coacting with previously mentioned special release magnet 30 (see Figs. 4 and 7). Energization of magnet 30 automatically operates key R to effect automatic release operation of the escapement and card carriage. At the same time, energization of magnet 30 in depressing lever 70, causes the latter to open contacts 30a (see Figs. 5 and 7) of the duplicating circuit, previously traced. Thus, operation of the release key mechanism prevents making of any duplicating circuits under control of the pattern card during ejection of the work card by release movement of the escapement mechanism.

Thus far, with the exception of those special parts to which attention has been called, the usual card punching mechanism has been described. The spot detecting means and the means for rendering defective cards unfit for further use will be explained now.

The spot detecting brushes 75 (Figs. 2, 5, and 7) are located directly behind the card carriage part 43 (see Fig. 5) and in front of the mouth of the supply magazine 48. The brushes are arranged in a line across the width of the card carriage so as to sense the entire width of the card. In the event a conductive spot of the card comes beneath brushes 75, the latter are conductively connected through the card spot to a contact plate 76 provided at the top of a lever 77 normally urged by a spring 78 in a clockwise direction (Fig. 2).

Detecting brushes 75 are mounted on a shaft 80 journaled in the frame for rotational movement. One end of shaft 80 (see Fig. 1) carries a crank arm 81 connected by a link 82 to an armature lever 83 acted on by a spring 84 and controlled by a magnet 85. Normally, spring 84 holds shaft 80 in counterclockwise position so that brushes 75 are lowered and in operative spot detecting position, indicated in Fig. 2. When magnet 85 is energized, it causes shaft 80 to rock clockwise (Fig. 1) thereby raising brushes 75 into inoperative card sensing position, indicated in Fig. 5.

Initially, magnet 85 is deenergized and brushes 75 are in lower, operative position. Now, as picker 50 feeds the bottom card T out of magazine 40, the card rides between brushes 75 and plate 76. Before the rear edge of the card is moved into position in front of card carriage pusher 46, the entire length of the card has passed brushes 75. Thus, should a conductive spot occur at any part of the card, it will be sensed by brushes 75 to form the following circuit (Fig. 7):

Spot detecting circuit.—From line 32, through a special switch 86, a feeler 87, the contact bar 88, brushes 75, contact plate 76, relay magnet 90, and through contacts 27 to line 24.

Before the card reaches brushes 75 and after leaving the brushes, the latter engage the bare contact plate 76. To avoid formation of a spot detecting circuit during these periods, the latter circuit is made through feeler 87 and contact bar 88. Contact bar 88 is fixed to the frame and has insulating portions at the front and rear ends. Feeler 87 is carried by bracket 51 of the picker mechanism and moves along bar 88 in correspondence with the movement of the picker mechanism and the card fed out of magazine 48 by picker 50. Feeler 87 wipes the conductive part of bar 88 only while the card is beneath brushes 75, thereby preventing making of the spot detecting circuit at other times.

When relay 90 is energized by the spot detecting circuit, it closes contacts 90a and 90b. Closing of contacts 90a forms a holding circuit through relay 90 which by-passes elements 75, 76, 87, and 88, so that after the defective spot passes the detecting brushes, relay 90 remains energized until contacts 27 open. Contacts 27 are known as the last column contacts and do not open until the last card column has passed the punches 15.

Thus, after a conductive spot has been detected, magnet 90 remains energized until the card has been ejected from the punching station. During this interval, relay contacts 90b also remain closed forming the following circuit:

From line 24, through last column contacts 27, signal 91, solenoid 92 (which controls the card

marring or cutting means to be described later), release magnet 30, contacts 90b, and through switch 86, to line 32.

The above circuit energizes release magnet 30, which as explained before operates mechanism for releasing the escapement bar 39 and the card carriage for continuous movement to the end of its forward stroke. However, while the picker mechanism is feeding the card to the card carriage, the escapement mechanism is concomitantly and positively being moved rearwardly. Thus, the release mechanism has no effect until the picker has moved the card to the card carriage at which time the return stroke of the carriage has been completed. With the card T delivered to the card carriage and the release magnet still energized, the escapement mechanism is released for immediate movement through its forward stroke, thus ejecting the card from the punching means. Further, energization of release magnet 30 has opened contacts 30a so that punching circuits cannot form under control of the pattern card during the aforesaid ejection of card T.

During ejection of the card, solenoid 92 is energized by the last described circuit. Referring to Figs. 1, 4, and 5, solenoid 92 is located in front of the punching station. Plunger 93 of the solenoid is connected by a linkage 94 to a lever 95 which rotatably carries a slitting disk 96. A spring 97 connected to lever 95 normally holds the slitter disk 96 elevated and clear of a co-operating slitter disk 98. Thus, normally, the card moves past the slitting disks without engaging the latter. When solenoid 92 is energized, it causes disk 96 to move down into cutting cooperation with disk 98. Now, as the card moves past the disks 96 and 98, the latter slit the card, marring it against further usage. When the forward, release, stroke of the card carriage has been completed and the ejected card reaches last column position, last column contacts 27 open to break the circuit of solenoid 92 and disk 96 returns to inoperative position.

Briefly, then, when a defective spot of the card is sensed by brushes 75, the release mechanism is operated to cause ejection of the card during which the duplicating circuits are prevented from forming and during which slitter disks 96 and 97 are operative to mar the defective card.

Picker 50, in order to deliver the card to card carriage pusher 46, must pass spot detecting contact plate 76. For this reason, contact plate 76 is carried by pivoted lever 77. Near the end, of its forward stroke, the picker 50 abuts plate 76 and actuates the plate counterclockwise (Fig. 2). The plate remains in cooperative position with brushes 75 until the rear edge of the card has passed brushes 76 and is then moved further by continued advance of the picker to the dot and dash position shown in Fig. 5. As lever 77 moved to the latter position, a lug 100 thereon moved into latching coaction with a latch lever 101 rigidly carried by a shaft 102. Lever 77 remains in the latched position, out of cooperation with brushes 75, until latch lever 102 is unhooked from lug 100.

Lever 102 is not unlatched from lug 100 until the picker on its return stroke has passed contact plate 76. For this purpose, bracket 51 of the picker mechanism is provided with a special rod 103 bent transversely at its free end. Near the end of the forward stroke of the picker mechanism, the bent end of rod 103 engages a by-pass pawl 104 (see Figs. 1 and 2) carried by an arm

105 secured to one end of shaft 102. As the bent end of rod 103 moves to the left and rides past the pawl 104, the latter is rocked clockwise without imparting movement to arm 105, shaft 102 and latch 101. During the return stroke of the picker mechanism, after picker 50 has passed the contact plate 76, the bent end of rod 103 engages pawl 104 and rocks it counterclockwise. This time the pawl transmits its movement to arm 105, shaft 102 and latch 101, thereby causing the latch to unhook lug 100 of lever 77, permitting spring 78 to return plate 76 to normal position.

In order to prevent brushes 75 from interfering with return movement of picker 50 and in order to prevent formation of spot detecting circuits during return of the picker, brushes 75 are lifted out of engagement with plate 76 until the picker has completed its return stroke. As explained before, contacts 63 (Fig. 6) are closed except when the picker mechanism is in rear, starting, position. Thus, while the picker is moving through its return stroke, contacts 63 are closed. Further, when contact plate 76 and its lever 77 were moved aside by picker 50 as the latter completed its forward stroke, the lower end of the lever cammed against an insulating strip 107 of a spring contact blade 108 and moved the blade towards a blade 109. Between them, blades 108 and 109 carry contacts 110. The contacts 110 are timed to close when the rear edge of the card has passed brushes 75. Now, with contacts 63 and 110 closed, the following circuit is formed (Fig. 7):

38 *Brush raising circuit.*—From line 32, through switch 86, contacts 63, contacts 110, brush lifting magnet 85 and to line 24.

Magnet 85, as previously explained, when energized raises brushes 75 to the inoperative position shown in Fig. 5. In their raised position, brushes 75 are out of the path of return movement of picker 50.

When latch 101 is released from lever 77 near the beginning of the return stroke of the picker mechanism, lever 77 returns to normal position and contacts 110 open. Magnet 85, however, is held energized through a stick circuit, as follows:

50 From line 24, through magnet 85, contacts 85a (closed by energization of magnet 85), contacts 63, and switch 86, to line 32.

The above stick circuit does not open until the picker mechanism reaches its starting position, at which time contacts 63 are opened to break the stick circuit.

Summary

The operator grasps finger grip 52 to move the picker mechanism through its forward stroke. Picker 50 feeds the bottom card T out of supply magazine 48. During the forward stroke of the picker, the card is moved past spot detecting brushes 75. In the event a conductive spot of the card is sensed by brushes 75, the spot detecting circuit is formed, causing energization of slitter-controlling solenoid 92 and release magnet 30. During the forward stroke of the picker, the card carriage is being moved through its return stroke. At the end of the forward stroke of the picker and the coincident end of the return stroke of the card carriage, the card is delivered to the carriage. Now, due to operation of release magnet 30, the escapement mechanism is released and immediately moves through its forward stroke with a continuous motion. The card is

thereby ejected from the punching station and while being ejected is marred by slitters 96 and 98 now in cooperation because of energization of solenoid 92. Also, during ejection of the card, the pattern card mechanism is ineffective to form punch duplicating circuits because of the opening of contacts 30a in the duplicating circuits. When the card has been ejected so that its last column has passed punches 15, last column contacts 27 open to break the circuits of solenoid 92, release magnet 30, and magnet 90.

During the return stroke of the picker mechanism, the brush raising circuits are formed to energize magnet 85 for raising detecting brushes 75 to permit the picker to pass and to prevent formation of spot detecting circuits. At the end of the return stroke of the picker mechanism, contacts 63 are opened to break the stick circuit of magnet 85. The parts are then in initial position.

While the invention has been disclosed in the preferred form, it is to be understood that such variations, changes, and departures as come within the scope of mechanical skill are within the field of the present invention. It is intended, therefore, to be limited only as indicated by the following claims.

I claim:

1. In combination; punching means to perforate record cards with selected data, means for detecting a defective card portion on its way to the punching means, means for ejecting the card from the punching means, and means controlled by the detecting means upon detecting a defective card portion for conditioning the ejecting means for card ejecting operation.

2. In combination; punching means to perforate record cards with selected data, means for detecting a defective card on its way to the punching means, means for ejecting the card from the punching means, means controlled by the detecting means upon detecting a defective card for conditioning the ejecting means for operation, and a device also controlled by the detecting means for marking the defective card during its ejection to denote its defectiveness.

3. In a machine in which automatic data duplicating means are provided to record duplicate data on record cards; the combination of means for detecting defective cards on their way to the duplicating means, means controlled by the detecting means for ejecting defective cards from the duplicating means, and means also controlled by the detecting device for disabling the duplicating means during ejection of the defective cards.

4. In a machine in which automatic data duplicating means are provided to record duplicate data on record cards; the combination of means for detecting defective portions of a card before such portions reach the duplicating means, and means controlled by the detecting means upon detecting defective portions of a card for disabling the duplicating means from operation.

5. In a machine in which punches are provided to perforate record cards under control of automatic data selecting means; the combination of means for detecting defective portions of a card before such portions reach the punches, and means controlled by the detecting means upon detecting defective portions of a card for disabling the automatic data selecting means.

6. In combination; punching means to perforate cards with selected data, means for detecting a defective card portion on its way to the punch-

ing means, a device for operating on a card to denote its defectiveness, and means controlled by the detecting means upon detecting a defective card portion for rendering said device effective for operation on the defective card.

5 7. In a machine having means for operating on a card; the combination of feeding means to normally feed a card step-by-step through said operating means to be operated upon, a card 10 supply magazine, mechanism for delivering a card from the magazine to the feeding means, means for detecting a defective card as the latter is being delivered to the feeding means, and means controlled by the detecting means upon 15 detecting a defective card for preventing step-by-step feed of the card by the feeding means.

8. In a machine having means for operating on a card; the combination of feeding means to feed a card step-by-step through the operating 20 means to be operated upon, a card supply magazine, mechanism for delivering a card from the magazine to the feeding means, means for detecting a defective card as the latter is being delivered to the feeding means, and means controlled by the detecting means upon detecting a defective card for preventing step-by-step feed of the card by the feeding means and causing continuous movement of the feeding means to eject the defective card delivered thereto.

30 9. In a machine of the class described; a card carriage for feeding a card, a card supply magazine, a reciprocatable picker for delivering a card during its forward stroke from the magazine to the carriage, card sensing means located between the magazine and the carriage for sensing a card for defective portions as the card is being delivered to the carriage, and means controlled by the sensing means upon sensing a defective card for manifesting the defectiveness of the card.

40 10. In a machine of the class described, a card carriage for feeding a card, a card supply magazine, a reciprocatable picker for delivering a card during its forward stroke from the magazine to the carriage, card sensing means located between the magazine and the carriage for sensing the card for conductive spots and past which the picker moves to complete its forward stroke, and means for automatically removing the sensing means from the path of the picker during the return stroke of the picker.

50 11. In a machine of the class described; a card carriage for feeding a card, a card supply magazine, means for delivering a card from the magazine to the carriage, card sensing conductive elements between which the card moves as the card is being delivered to the carriage for sensing defective spots in the card, a circuit closed by the conductive elements upon sensing a conductive spot, and means controlled by the circuit for manifesting on the same card the fact of the defective spot occurring on the card.

55 12. The machine as defined in claim 11, said card delivering means comprising a card picker having a forward stroke for delivering the card and a return stroke to return to the starting position, and contact means for timing the period during which the aforesaid conductive elements may form said circuit and including a contact element connected to the picker for movement synchronous with the picker movement.

60 13. In a machine having means for operating on a card; the combination of means detecting a defective card on its way to aforesaid operating means, means controlled by the detecting means upon detecting a defective card for mani-

festing defectiveness of the card, and means also controlled by the detecting means for disabling the aforesaid operating means from operating on a defective card.

14. In a machine having punching means to punch record cards with selected data; the combination of a card carriage for feeding a card through the punching means, means for delivering a card to the carriage, means for detecting a defective portion of the card as the latter is being delivered to the carriage, and means controlled by the detecting means upon detecting a defective card portion for manifesting the defectiveness of the card.

15. In a card punching apparatus; the combination of means for punching a card with coded designations, means for detecting defective portions of a card prior to such portions reaching the punching means, and means controlled by the detecting means upon detecting a defective card for manifesting its defectiveness.

16. A machine for operating on statistical cards having index point positions; comprising punching means to perforate the index positions of the cards, one card at a time, to represent selected information in coded form, in combination with means to detect a defective card, and means controlled by the detecting means to manifest defectiveness of the card, said manifesting means including a device for marring the defective card to prevent its subsequent use.

17. A machine for operating on statistical cards having index positions; comprising punching means to perforate the index positions of the cards, one card at a time, to represent selected information in coded form, in combination with means for detecting defective portions of a card on their way to the punching means, and means controlled by the detecting means for manifesting defectiveness of the card portions, said manifesting means including a cutting device for cutting the defective card to render it unfit for further use.

18. In a machine operating on statistical cards; means to record information on said cards, and means for ejecting the cards, in combination with means to detect defective cards running through the machine and means controlled by the detecting means upon detecting a defective card for conditioning the ejecting means to eject such card and simultaneously disabling the recording means from operating during such ejection.

19. In a machine operating on statistical cards having columns of index positions; means to punch the index positions of the cards selectively to record data in coded form and means to eject the cards, in combination with means for detecting a defective card in the machine and means controlled by the detecting means for conjointly conditioning the ejecting means to eject the defective card and disabling the punching means from operating during such ejection.

20. In a machine operating on a statistical record sheet having columns of index positions; punches to punch the columns of the sheet, one column at a time, and sheet feeding means operable to feed the sheet column-by-column past the punches to enable the latter to punch the columns in succession, in combination with means to detect a defective sheet portion and means controlled by the detecting means upon detecting a defective sheet portion for preventing a

column-by-column feed of the sheet by said feeding means.

21. In a machine operating on a statistical record sheet having columns of index point positions; punches to perforate the index positions of the sheet with data representations and a set of selectors for selecting the punches to operate in accordance with the data to be represented on the sheet, in combination with means to detect a defective sheet portion and means controlled by the detecting means upon detecting a defective sheet portion for preventing operation of said set of selectors.

22. In a card punching machine operating on a statistical record sheet having columns of index point positions; punching means to perforate the index point positions of the columns to represent information in coded form in combination with means to detect defective unpunched material of the sheet in the punching machine and means controlled by the detecting means upon detecting defective unpunched sheet material for manifesting defectiveness of the sheet. 10

CLEMENT EHRET.
